TOBACCO PIPE

Homer Gamache and Harrison Hance, Newark,
N. J.; said Hance assignor to said Gamache

Application February 11, 1933, Serial No. 656,234

9 Claims. (Cl. 131—12)

This invention relates to that type of tobacco pipe including a bowl for the tobacco and a stem to permit flow of smoke from the bowl to the mouth of the smoker, and more particularly this invention relates to such pipes which are constructed to retard or prevent flow of juices or liquid either from the bowl of the pipe through the stem into the mouth of the smoker or from the mouth into the bowl. The invention also is related to smokers' pipes embodying constructions whereby the bowl and stem can be easily and thoroughly cleaned.

One object of the invention is to provide a smoker's pipe of the general character described which shall have a separable bottom for the bowl to which is integrally connected an extension to removably fit the stem of the pipe and constructed to obstruct or retard flow of liquids through the stem, whereby the bowl and stem can be easily and quickly cleaned and liquids will be retarded from flowing through the stem.

Another object is to provide a smoker's pipe of the character described which shall comprise a minimum number of novel and improved simple parts which can be easily and quickly assembled.

Further objects are to provide a smoker's pipe which shall have a separable bottom for the bowl which can be connected to and disconnected from the bowl by a simple sliding motion in a direction at an angle to the axis of the bowl; to provide such a pipe which shall have an integral liquid flow retarding extension that can be slid into and out of the opening in the pipe stem simultaneously and in the same operation with the application and removal of said separable bottom to and from the bowl respectively; and to provide a pipe of this character wherein said separable bottom and said extension shall be held in position in the pipe by separable connection of said extension to the bit or mouthpiece of the pipe.

Other objects of the invention are to provide in a pipe of the character described a novel and improved construction and combination of a bowl and a separable bottom therefor; to provide in a smoker's pipe a novel and improved device for obstructing the flow of liquid through the stem of the pipe and for collecting such liquid; to provide such a device which automatically cleans the stem of the pipe as the device is removed from the stem of the pipe; and to obtain other advantages and results as will be brought out by the following description.

Referring to the accompanying drawing in which corresponding and like parts are desig-

nated throughout the several views by the same reference characters.

Figure 1 is a vertical longitudinal sectional view through a smoker's pipe embodying our invention.

Figure 2 is a transverse vertical sectional view on the line 2—2 of Figure 1.

Figure 3 is a similar view on the line 3—3 of Figure 1.

Figure 4 is a detached perspective view of the separable bottom and liquid flow obstructing extension and.

Figure 5 is a side elevation of the pipe bowl and stem with the separable bottom and mouth piece removed.

Specifically describing the illustrated embodiment of the invention, the reference character 1 designates the main portion of the bowl of the pipe which has an integral stem 2 projecting laterally therefrom at approximately right angles to the axis of the bowl. The stem 2 has a smoke passage 3 to communicate with the interior of the bowl. The bottom end 4 of the bowl is disposed in a plane at approximately right angles to the axis of the bowl, and the stem is connected to the main portion of the bowl beyond said bottom end 4 and has one end 5 disposed adjacent to the bottom end 4 of the main portion of the bowl and at an angle thereto.

A separable bottom 6 is provided for the bowl and is fitted in air-tight relation to the bottom end 4 of the main portion 1 and the end 5 of the stem 2. Preferably, as shown, this separable bottom 6 is applicable to and removable from the main portion of the bowl by relative sliding of the main portion and the separable bottom parallel to the plane of the bottom end 4 and respectively toward and from the stem 2. As shown, the bottom end of the main portion 1 of the bowl may have a rabbet 7 and a groove 8, while the separable bottom 6 may have a flange 9 to fit the rabbet 7 and a tongue 10 to fit the groove 8. Also, the end of the stem 2 may have a groove 11 to receive a tongue 12 on the corresponding end of the separable bottom 6.

To securely hold the separable bottom 6 on the bowl, said bottom is formed with an extension 13 which is arranged in the smoke passage 3 of the stem and has a screw threaded end 14 projecting beyond the outer end of the stem upon which is screw-threaded a mouth piece or bit 15 which has an abutting relation to the end of the stem. With this construction, when the mouth-piece 15 is screwed upon the threaded end 14 of the extension 13, said extension is drawn through the

smoke passage and the separable bottom 6 is drawn into snug air-tight engagement with the bottom end of the main portion 1 of the bowl and the end of the stem. The projecting end 14 of the extension 13 has a smoke passage 16 which communicates with the smoke passage 3 of the stem 2 and a similar passage 17 in the mouth piece.

The extension 13 may also serve to obstruct or retard the flow of liquid through the smoke passage 3, and as shown, said extension is approximately cylindrical and has longitudinally spaced portions at the top thereof cut away to form shoulders 18 and grooves 19 to obstruct the flow of liquid through the smoke passage and to collect such liquid, respectively. For permitting smoke to freely pass through the smoke passage 3, the upper portions of the edges of the shoulders 18 may be formed with notches 20 to permit passage of smoke between the extension 13 and the walls of the smoke passage.

With this construction, it will be seen that the removable bottom 6 and the extension 13 may be applied to and removed from the main portion 1 of the bowl and the smoke passage 3 of the stem, respectively, at the same time and in the same operation, by simple sliding of the extension 13 in the smoke passage 3 and sliding of the separable bottom 6 upon the bottom end of the main portion 1 of the bowl. Upon removal of the separable bottom 6 from the bowl, the bowl can be thoroughly cleaned and the separable bottom may also be cleaned, and as the parts are separated the extension 13 will scrape liquid and solid particles from the walls of the smoke passage 3.

The pipe embodying the invention comprises only three simple and inexpensive parts which can be easily and quickly assembled and disassembled, and the construction and combination of parts enables the pipe to be easily and thoroughly cleaned.

While we have shown and described the invention as embodied in certain details of construction, it should be understood that this is primarily for the purpose of illustrating the principles of the invention and that many modifications and changes may be made in the details of construction without departing from the spirit or scope of the invention.

Having thus described our invention, what we claim is:

1. A smoker's pipe comprising a bowl having a main portion and a stem having a smoke passage, said main portion being formed at one end adjacent said stem to receive a separable bottom, a separable bottom fitted on said end of said main portion and having an extension in said smoke passage in said stem, and a mouthpiece connected to said extension and said stem.

2. A smoker's pipe comprising a bowl having a main portion and a stem having a smoke passage, said main portion being formed at one end adjacent said stem to receive a separable bottom, a separable bottom fitted on said end of said main portion and having an extension in said stem which has a screw threaded end projecting beyond the end of the stem, and a mouth piece screw-threaded upon said extension and abutting said end of the stem.

3. A smoker's pipe including a main bowl portion having a flat bottom end at approximately right angles to its axis, and an integral stem

approximately right angularly disposed beyond said flat end and having a coaxial smoke passage, one end of said stem being adjacent and in a plane at an angle to said bottom end of the main bowl portion, and a separable bottom fitted on said main bowl portion in air tight relation to said bottom end of the main bowl portion and said end of the stem, said separable bottom for said bowl having an extension in said smoke passage in the stem, and a mouth piece at the other end of said stem connected to said extension and abutting said stem for holding said separable bottom in position.

4. The smoker's pipe set forth in claim 3 wherein said extension is approximately semi-cylindrical to nicely fit said smoke passage and has longitudinally spaced portions transversely cut away to form shoulders and grooves for obstructing the flow of liquid through said smoke passage and for collecting such liquid, and means for permitting smoke to flow between said extension and the walls of said smoke passage.

5. The smoker's pipe set forth in claim 3 wherein said extension is approximately semi-cylindrical to nicely fit said smoke passage and has longitudinally spaced portions transversely cut away to form shoulders and grooves for obstructing the flow of liquid through said smoke passage and for collecting such liquid, and notches in the upper edges of said shoulders for permitting smoke to flow between said extension and the walls of said smoke passage.

6. The smoker's pipe set forth in claim 3 wherein said extension has a screw-threaded end and a smoke passage therethrough, and said mouthpiece is screw-threaded upon said threaded end of said extension in abutting relation to said stem.

7. A smoker's pipe including a main bowl portion having a flat bottom end at approximately right angles to its axis, and an integral stem approximately right angularly disposed beyond said flat end and having a coaxial smoke passage, one end of said stem being adjacent and in a plane at an angle to said bottom end of the main bowl portion, and a separable bottom fitted on said main bowl portion in air-tight relation to said bottom end of the main bowl portion and said end of the stem, said separable bottom having an extension in said smoke passage, and means cooperating with said extension for holding said separable bottom in said position.

8. A smoker's pipe comprising a bowl and a stem connected to the bowl and having a smoke passage communicating therewith, said bowl including a main portion and a separable bottom having an integral extension in said smoke passage which is constructed to permit smoke to flow through said smoke passage and to obstruct flow of liquid through said smoke passage, and means for connecting said main portion and said bottom together upon sliding of said bottom relatively to said bowl in the direction toward said stem.

9. A smoker's pipe as set forth in claim 8 wherein said extension has a screw threaded extremity projecting beyond said stem, and with the addition of a bit or mouth-piece screw threaded upon said extension and abutting the end of said stem.

HOMER GAMACHE.
HARRISON HANCE.
